DOMINICK PECCERILLO, OF NEW HAVEN, CONNECTICUT.

CONTROL SYSTEM.

Application filed January 31, 1927. Serial No. 164,899.

My invention relates to motor-control systems, and particularly to that class of control systems which are employed in connection with elevators, hoists, and similar apparatus. The object of my invention is to provide a control system in which an automatic leveling-device may be cut into and out of action by means of a manually-operable master-control-switch which is mounted in the car for governing its operation, whereby the additional effort and loss of time, incident to the manipulation of separate means, is avoided. With this general object in view, my invention consists in a control system characterized by having a master-control-switch for controlling the ordinary movements of the car, which, in one position, will divert a control-current through an automatic leveling-switch operable by the movement of the car, and when in another position will render the said leveling-switch ineffective by causing a control-current to flow through an independent channel, whereby both the normal control and the automatic leveling may be accomplished by means of a single handle.

My invention further consists in a control system characterized as above and having certain other details of construction and combinations of parts as will be hereinafter described and particularly recited in the claims.

I am aware that control systems have been proposed in which the car is automatically leveled by means of an automatic leveling-switch which is rendered effective or ineffective by means of a manually-operable second switch separate and distinct from the master-control-switch and usually cut into and out of play by the movements of a door. Such control systems, however, are not only mechanically and electrically complex, but in some respects are futile and occasion considerable loss of time to the passengers. Thus, if the action of the leveling-device is dependent upon the movement of the door, it very often happens that the passengers leave and enter the car the instant that the door is opened and before the leveling-device has had time to perform its function.

Under my invention, as will hereinafter appear, the leveling-device is brought into play by merely moving the master-control-switch so as to break the normal control-circuits. The leveling-device thus has ample time to complete its function before, in the

normal course of events, the door can be opened.

In the accompanying drawings:

Fig. 1 is a diagrammatic view of a control system embodying my invention, the parts being shown in the positions due to them when the car is traveling in the "down" direction;

Fig. 2 is a broken view corresponding to Fig. 1, but with the master-control-switch in the position in which it disconnects the normal control-circuits and in which it has placed the car, which has stopped slightly below the floor-level, under the control of the automatic leveling-switch, which will immediately function to move the car in the "up" direction to bring it level with the floor;

Fig. 3 is a corresponding view, the parts being in the positions due to them after the automatic leveling-switch has leveled the car; and

Fig. 4 is a view corresponding to Fig. 1 but showing a different form which a control system constructed in accordance with my invention may assume.

In Figs. 1, 2 and 3 of the drawings, I have shown my improved control system associated with an automatic stop-mechanism and circuit of the type shown in my co-pending application, filed January 21, 1926, Serial No. 82,748, and patented February 8, 1927, No. 1,616,821 in which the driving-motor consists of an armature 10 and a field-magnet-winding 11, which latter is operatively connected to a positive line-conductor 12 and to a negative line-conductor 13 in the usual manner. A resistor 14 is interposed in the circuit through the armature during the starting period. This resistor is cut out of the armature-circuit shortly after the start of the motor by a slow-acting automatic switch 15, also in the usual manner.

The current is sent through the armature 10 in one direction, as for instance to cause the motor to drive the car upward, by an automatic switch 16 having double contacts, as shown, and operated by what I shall call the "up-control" solenoid 17. Current is also sent to the armature but in the opposite direction by an automatic switch 18 having double contacts as shown, and operated by a solenoid 19, which I shall designate the "down-control" solenoid. One terminal of each of the solenoids 17 and 19 is connected

by a conductor 20 to the negative line-conductor 13. The opposite terminal of the up-control solenoid 17 is connected by a conductor 21 to the up-control contact 22 of the 5 master-control-switch 23, which is mounted in the elevator car, generally designated by the numeral 24, and moving in a shaftway 25. The remaining terminal of the down-control solenoid 19 is connected by a conductor 26 to the down-control contact 27 of the master-control-switch 23. The conductor 21 of the up-control solenoid 17 is also connected by means of a conductor 28 to an up-control contact 29 of an automatic leveling-switch 30 carried by the car, the inner down-control contact 31 of the switch being connected by a conductor 32 to the conductor 26 of the down-control solenoid 19.

The automatic leveling-switch above referred to comprises a lever 33 pivotally mounted in a clip 34 and carrying at its inner end a contact 35 adapted to alternately engage either of the contacts 29 and 31 aforesaid, and carrying at its outer end 25 a roller 36 which is adapted to co-act with a series of leveling-cams 37, one of which is located near each floor-level. Each of these cams (only one of which is shown) is formed with a neutral step 38 and an up-control 30 step 39. The contact 35 of the switch-lever 33 is normally held in engagement with down-control contact 31 by means of a spring 33a.

The clip 34, which mounts the pivotal lever 33, is connected by a conductor 40 to a contact 41 of the master-control-switch, which latter contact is adapted to be electrically connected to a complementary contact 42 by means of the switch-blade 43 formed upon 40 the inner end of the control-lever 44, which is pivoted, as at 45, and carries the control-handle 46 at its outer end in the usual manner. The contact 42 just referred to is connected by a conductor 47 to the auxiliary contact-arm 48 of an automatic stop-switch 49 mounted upon the car and fully described in my co-pending application above referred to, and which needs no further description other than to say that it is intended to effect the automatic stoppage of the car under certain conditions, as is outlined in the two succeeding paragraphs, and comprises a lever 50 pivoted in a clip 51 and carrying at its lower end a contact 52 adapted to engage the auxiliary contact 48 aforesaid but normally held in engagement with an inner contact 53 by means of a spring 54. The outer end of the lever 50 is provided with a roller 55 adapted to engage a cam 56 as the car moves in the shaftway 25.

If it is desired to effect an automatic stop of the car when traveling in the down direction, just before reaching the desired floor-level the control-handle 46 is moved 65 into the position indicated by broken lines

in Fig. 2, so as to cause the switch-blade 43 to connect the down-control contact 27 with the central-contact 70 of the master-control switch. In this position of the control-handle, the automatic stop-switch 49 is placed in series with the master-control switch so that the control-current is forced to pass through the automatic stop-switch on its way to the down-control solenoid 19. In this position of the handle 46, the path 75 of the control-current would be as follows: from the main-line conductor 12 through the conductor 59, clip 51, lever 50, contacts 52 and 53, conductors 71, contacts 70, switch-blade 43, contact 27, conductor 26, and 80 through the down-control solenoid 19. Now, when in its downward travel with the car, the roller 55 of the stop-switch 49 strikes the cam 56, the lever 50 will be rocked with the effect of separating the contacts 52 and 53 and so automatically breaking the control-circuit to the down-control solenoid and hence stop the car.

Similarly, if the car is traveling upward and if it is desired to make an automatic stop, the handle 46 of the master-control switch is moved so as to cause the switch-blade 43 to connect the up-control contact 22 and the central-contact 70, so that here again the automatic stop-switch is placed in series 90 with the automatic master-control switch 23, so that the control-current is forced to travel from the main-line conductor 12 through the parts 59, 51, 50, 52, 53, 71, 70, 43, 22 and 21 to the up-control solenoid 17. When the 100 roller strikes the cam 56, the control-current will be automatically broken as above and the upward travel of the car stopped.

The positive main-line conductor 12 extends to the master-control-switch 24 aforesaid, where it is connected to two contacts 57 and 58, with which, however, the present invention is not concerned. A short conductor 59 also connects the main line-conductor 12 to the clip 51 aforesaid.

With the construction shown in Figs. 1 to 3 inclusive, and assuming that the car is traveling in the "down" direction and that the operator wishes to stop at the floor-level 60, this he may do by moving the control-lever 44 from the position in which it is shown in full lines, into the position in which it is shown by broken lines in Fig. 1. This movement of the lever 44 will disconnect the direct control-circuit and will couple the leveling-switch 30 and automatic stop-switch 49 in series with each other and with the contacts 41 and 42 of the master-control-switch, whereby, when the switches 30 and 49 are actuated as will be shortly described, the current from the main line-conductor will be compelled to pass through the conductor 59, clip 51, lever 50, contact 52, contact-arm 48, conductor 47, contact 42, switch-blade 43, contact 41, conductor 40, clip 34, lever 33, 120 contact 41, conductor 40, clip 34, lever 33, 130

and contact 35, before it can energize either of the solenoids 17 or 19, as may be required to effect the raising or lowering of the car, dependent upon whether it has stopped below or above the desired floor-level. If the car has stopped below the floor-level, the control-current will continue its flow from a contact 35 through the contact 29, conductors 28 and 21 to the up-control solenoid 17. On the other hand, if the car has stopped above the floor-level, the control-current will continue its flow from the contact 35 through the contact 31, conductors 32 and 26 to the down-control solenoid 19.

With the master-control switch in the position shown by broken lines in Fig. 1 and by full lines in Fig. 2, the continued downward travel of the car, due to its momentum, from the position shown in Fig. 1 into the position shown in Fig. 2 (in which latter it has moved slightly below the floor-level 60), will cause the roller 55 at the outer end of the lever 50 to engage the cam 56, with the effect of moving the contact 52 into engagement with the auxiliary contact 48. This downward movement of the car will also cause the roller 36 at the outer end of the lever 33 to ride up upon the step 39 of the leveling-cam 37, whereby the up-control solenoid 17 will be energized for moving the car in the "up" direction by the current flowing to it from the main line-conductor 12, through the short conductor 59, clip 51, lever 50, contact 52, auxiliary contact 48, conductor 47, contact 42, switch-blade 43, contact 41, conductor 40, clip 34, lever 33, contact 35, up-control contact 29, conductor 28, and conductor 21. This energization of the up-control solenoid will cause the car to move upward until the roller 36, at the outer end of the lever 33, rides off of the step 39 of the cam 37 and onto the neutral step 38 thereof, whereby the supply of current to the up-control solenoid is automatically shut off. The parts will now occupy the position shown in Fig. 3.

Conversely, should the car have been traveling in the "up" direction and overridden the floor at which it is desired to stop, the contact 35 would be held in engagement with the contact 31 by the spring 33^a so as to energize the down-control solenoid for moving the car downward until the roller 36, at the outer end of the lever 33 engages the cam 37 and rides up upon its neutral step 38, with the effect of moving the contact 35 out of engagement with the contact 31 and into its neutral position shown in Fig. 3, so that current can reach neither of the two solenoids 17 or 19 by this route.

To start from the floor, the operator merely moves the switch-lever 44 so that its blade 43 connects either the contacts 27 and 58 or the contacts 22 and 57, dependent upon the desired direction of travel, so that the control-current may pass through direct paths,

independent of the action of either of the automatic switches 30 or 49. Thus, if it is desired to cause the car to move in the up direction, the switch-blade 43 is moved so as to connect the contacts 22 and 57 so that the control-current will flow from the main-line conductor 12 through the contact 57, blade 43, contact 22, conductor 21 to the up-control solenoid 17. If, on the other hand, it is desired to cause the car to move in the down direction, the switch-blade 43 is moved so as to connect the contacts 58 and 27 so that the control-current will flow from the main-line conductor 12 to the down-control solenoid 19 by way of the contact 58, blade 43, contact 27 and conductor 26.

In the foregoing description of operation, I have omitted describing, for the sake of clarity, the functioning of the automatic stop-switch 49 as such, and have only described its action in so far as it affects the automatic leveling-switch by the engagement of its movable contact 52 with the auxiliary contact 48, which latter is connected to the automatic leveling-switch as shown.

If the operator desires to cause the car to stop automatically at any given floor, when the car is traveling in the down direction, for instance, he may accomplish this by moving the handle 46 of the master-control-switch into its intermediate position, in which it is indicated by broken lines in Fig. 2, before moving it into its central position, as shown by full lines in the same figure, so as to place the contacts 52 and 53 of the automatic stop-switch in series with the master-control-switch, with the result that the control-current will be broken and the car stopped when the cam 56 moves the contact 52 away from the contact 53 as hereinbefore described.

The control system shown in Fig. 4 is one having the same characteristics as that shown in the preceding figures, but is arranged to function independently of the automatic stop-switch, which is the feature of my co-pending application above referred to, and not necessarily combined with my present invention (though preferably). In this arrangement of parts, the lever 33 is provided with a pin 61 embraced by a U-shaped centering-spring 62 which tends to maintain the contact 35 at the lower end of the lever in a neutral position between the contacts 29 and 31. The roller 36 at the outer end of the lever 33 enters a cam-groove 63 in one face of a block 64. The cam-groove 63 aforesaid comprises a down-control reach 65 which is adapted to hold the contact 35 in engagement with the down-control contact 31, a neutral reach 66, and an up-control reach 67, which is adapted to hold the contact 35 in engagement with the up-control contact 29. Under this arrangement of parts, the contact 42 is directly con-

nected to the main line-conductor 12, as shown.

Should the car be brought to a stop slightly below the floor-level, the roller 36 of the lever 33 will be located in the up-control reach 67 of the block 64, with the effect of holding the contact 35 in engagement with the contact 29, so that current will reach the up-control solenoid 17 by flowing from the main line-conductor 12 through the contact 42, switch blade 43, contact 41, conductor 40, clip 34, lever 33, contact 35, contact 29, conductor 28, and conductor 21, with the effect of causing the car to move upward until the roller 36 engages the neutral reach 66 of the block 64, at which time the contact 35 will be located midway between the two contacts 29 and 31.

In the event that the car should override the floor at which it is intended to stop when traveling in the "up" direction, the down-control reach 65 of the cam-groove 63 will serve to hold the lever 33 so that its contact 35 is in engagement with contact 31, with the effect that the down-control solenoid will be energized so as to cause the car to move downward until the roller 36 engages the neutral-reach 66 of the cam 64.

I wish to call attention to the fact that in the control systems shown in Figs. 1 to 3 inclusive and in that shown in Fig. 4, the master-control-switch possesses the capacity of connecting itself in series with the automatic leveling-switch 33, so that the latter is rendered effective or ineffective by the former.

From the foregoing it will be seen that under my invention it is only necessary to manipulate the master-control-switch by means of its single handle 46 to cause the car to operate in its normal way in either the "up" or "down" direction, or to bring the automatic control-switch into action. By my invention, therefore, the automatic control-switch is enabled to come into action so closely after the shutting off of the main control-circuits that the car is brought into alignment with the desired floor-level before, in the normal course of events, the operator of the car has had time to open a door to permit passengers to either leave or enter the car.

I claim:

1. A control system, including a car; a motor therefor; a plurality of control-circuits for the said motor; an automatic leveling-switch operable by the movement of the car; a master-control-switch carried by the said car and manually operable by means of a single handle, which when in one position will cause a motor-control current to flow through the said automatic leveling-switch which is thereby placed in series with the said master-control-switch, and when in

another position will render the said automatic leveling-switch ineffective by causing a control-current to flow through a channel which is independent of the said leveling-switch.

2. A control system, including a car; a motor therefor; an automatic leveling-switch operable by the movement of the car; a master-control-switch carried by the said car and manually operable by a single handle, by means of which it may connect itself in series with the said automatic switch, and a control-circuit governed by the said master-control-switch and including an "up-control" solenoid and a "down-control" solenoid and having two channels of flow, one of said channels including both the said master-control-switch and the automatic leveling-switch, and the other channel being independent of the said leveling-switch.

3. A control system, including a car; a motor therefor; an automatic leveling-switch operable by the movement of the car; a second automatic switch also operable by the movement of the car; a master-control-switch carried by the said car and manually operable by a single handle, which when in one position will place the said automatic leveling-switch and the said second automatic switch in series with the said master-control-switch and when in another position will render the said automatic switches ineffective by causing the control-current to flow through a channel which is independent of the said automatic switches.

4. A control system, including a car; a motor therefor; a plurality of control-circuits for the said motor; an automatic leveling-switch operable by the movement of the car; a master-control-switch carried by the said car and manually operable by means of a single handle, which when in one position will cause a motor-control current to flow through the said automatic leveling-switch, and when in another position will render the said automatic leveling-switch ineffective by causing a control-current to flow through a channel which is independent of the said leveling-switch.

5. A control system, including a car; a motor therefor; an automatic leveling-switch operable by the movement of the car; a master-control-switch carried by the said car and manually operable by a single handle, and a control-circuit governed by the said master-control-switch and including an "up-control" solenoid and a "down-control" solenoid and having two channels of flow, one of said channels including both the said master-control-switch and the automatic leveling-switch, and the other channel being independent of the said leveling-switch.

6. A control system, including a car, a motor therefor, an automatic leveling-switch operable by the movement of the car, an

- automatic stop-switch also operable by the movement of the car, a master-control-switch carried by the said car and manually operable by a single handle which, when in one position, will cause a control-current to flow through the said automatic leveling-switch, so as to be controllable thereby, and when in a second position, to cause a control-current to flow through the said automatic stop-switch, so as to be controllable thereby, and when in a third position to render both of the said automatic switches ineffective by a control-current to flow through a channel which is independent of the said automatic switches. 7. A control system, including a car, a motor therefor, an automatic leveling-switch operable by the movement of the car and including a movable contact and two stationary contacts, a spring for holding the said movable contact in a neutral position between the said stationary contacts, and a cam for positively moving the said movable contact into engagement with either of the said stationary contacts, a master-control-switch carried by the said car and manually operable by a single handle, which, when in one position, will cause a motor-control-current to flow through the said automatic leveling-switch and when in another position will render the said automatic leveling-switch ineffective by causing a control-current to flow through a channel which is independent of the said leveling-switch. 20 25 30 35
- In testimony whereof, I have signed this specification.

DOMINICK PECCERILLO.
